UNITED STATES PATENT OFFICE

146,824

DESIGN FOR A SPOON

Jay L. Goodwin, Tujunga, Calif.

Application June 17, 1946, Serial No. 130,818

Term of patent 7 years

(Cl. D54—12)

To all whom it may concern:

Be it known that I, Jay L. Goodwin, a citizen of the United States, residing at Tujunga, in the county of Los Angeles and State of California, have invented a new, original, and ornamental Design for a Spoon, of which the following is a specification, reference being had to the accompanying drawing, forming a part thereof in which:

Fig. 1 is a top view of a spoon, showing my new design;

Fig. 2 is a side view of the spoon;

Fig. 3 is an end view of the spoon as seen from the handle end; and

Fig. 4 is an end view of the spoon as seen from the spoon end thereof.

I claim:

The ornamental design for a spoon, as shown.
JAY L. GOODWIN.
